(57) **CLAIM**

The ornamental design for a collapsible nasal irrigation container, as shown and described.

DESCRIPTION

FIG. 1 is a front elevation view of a collapsible nasal irrigation container showing my new design, the back elevation view being a mirror image thereof.

FIG. 2 is a left side elevation view thereof, the right side elevation view being a mirror image thereof.

FIG. 3 is a top plan view thereof; and,

FIG. 4 is a bottom plan view thereof.

The dotted lines shown in FIGS. 1-4 showing the spout and cap are included for the purpose of illustrating portions of the container that form no part of the claimed design.
